UNITED STATES PATENT OFFICE.

JOHN McDONALD AND FRANK H. McBRIDE, OF BLAIR TOWNSHIP,
WASHINGTON COUNTY, NEBRASKA.

MUD-TOE FOR TRACTION-WHEELS.

No. 852,573.

Specification of Letters Patent.

Patented May 7, 1907.

Application filed April 16, 1906. Serial No. 311,942.

To all whom it may concern:

Be it known that we, JOHN McDONALD and FRANK H. McBRIDE, citizens of the United States, residing near Blair, in Blair township, in the county of Washington and State of Nebraska, have invented a new and useful Adjustable and Foldable Mud-Toe or Grouter for Traction-Wheels, of which the following is a specification.

Our invention relates to improvements in toe or grouter attachments for traction-wheels to increase their foothold on earth roads; especially to a toe or grouter that can be readily applied to the wheels of traction-engines now in use; and the objects of our improvement are first, to provide a grouter with an adjustable base to facilitate its attachment to the variously constructed traction-wheels now being used; and second, to supply foldable toes to project beyond the regular fixed toes of the traction-wheel and that may easily and quickly be folded away from the tread of the wheel, without being detached therefrom, when they are not needed. We obtain these objects by the mechanism illustrated in the accompanying drawings, in which—

Figure 1 is a perspective view of a portion of the rim and spokes of a traction-wheel with the foldable grouter attached and folded; Fig. 2, is an inside view looking from the hub toward a segment of the rim, showing the adjustable base of the grouter attached; and Fig. 3 is a side elevation of the foldable grouter and toe separated from the base or attaching part.

Similar numerals refer to similar parts throughout the several views.

The treads of traction-wheels are usually provided with the toes 4, 4, etc., to cut into the path of the wheel to prevent slipping. On muddy roads or soft fields the spaces between these toes become filled with earth and thereby the toes become ineffectual. To overcome this slipping a less number of farther projecting toes or grouters have been temporarily attached. These have generally been difficult to attach and necessarily removed in crossing wooden bridges or cross-walks which would be broken by the concentrated load on the toes of the grouters, which are placed farther apart than the regular toes, and consumed much time in attaching and detaching. We have overcome this dif-

ficulty by a construction in which the grouter proper is made a separate part hinged to an adjustable attaching base-part whereby the grouter may be turned to project from the tread of the wheel, as indicated by the broken lines 23 in Fig. 1, or folded within the body of the wheel entirely out of the way, as shown in the same view.

The attaching part consists of a body or stem 5 disposed centrally between the spokes 2' and 2'' crosswise on the inner periphery of the rim 3 of the wheel. One end has the integral outward-turned hook 7 to engage the edge of the rim, the point side of the hook overlapping the tread of the wheel. The opposite end has the inward projecting lug 13 perforated to receive the threaded legs of the U-shaped yoke 12 which is looped around the spoke 2 toward the opposite edge of the rim. By the nuts 14 on the threaded legs of the yoke the attachment is adjusted to any width of rim and the hook 7 is drawn into fixed engagement with the edge of the rim and the attaching base held firmly in position. This base has the integral enlargement 6 to strengthen the base of the hook and carry the pintle 22 and also has the integral brace or strengthening rib 19 throughout its length as shown.

The foldable toe or grouter part consists of a bifurcate body having the parallel branches 16 and 16 united by a V-shaped base 17 terminating in the toe 18. The branches are perforated to receive the ends of the pintle 22 disposed through the enlargement 6 between the branches to hinge the parts together. The V-shaped base and toe are further strengthened and supported by the bridge or cross-brace 21, the bevel sides 9 and 9 of the hook which are impinged by the inner walls 17 and 17 and the outside 8 of the hook on which rests the edge of the brace 21 when the grouter is turned outward for service. The surfaces 8, 9 and 9 are curved, as shown, concentric with the pintle, so that the grouter swings to a perfect close seat thereon; and the notches 20 in the edges of the branches 16 engage the edge and tread of the rim to further support the grouter when in use.

The surface 8, of the point side of the hook which forms a seat block on the tread of the wheel for the grouter toe, is not higher than the regular toes 4, therefore, does not interfere with the ordinary use of the wheel.

A projecting eye 11 on one branch of the grouter and a like eye 10 on the adjacent side of the base 5, serve to attach the ends of the coil spring 15 which by its resilience retains 5 the grouter in the folded position shown in Fig. 1. This spring yields to allow the toe 18 to swing around on the broken line 24 bringing the grouter to the position indicated by the broken lines 23 where it is again retained 10 by the spring which is then disposed across and against the inner periphery of the rim by which it is protected from injury.

I claim—

1. A foldable grouter for traction-wheels 15 having in combination an attaching base, a mud-toe hinged to said base and a spring connected to retain the toe extended or to retain it folded upon said base.
2. An adjustable attaching base for a traction-wheel grouter, having in combination, a hook to engage the edge of the rim of the wheel, a U-shaped yoke to engage a spoke of the wheel, the legs of said yoke disposed through a lug on the body of the hook and 25 nuts threaded on said legs.
3. A foldable grouter attachment for traction-wheels having in combination, an attaching base with a hook to engage the edge of the wheel-rim, a bifurcate grouter part 30 having a V-shaped base fitted to straddle the

overlapping point of the hook to form a mud-toe projecting from the tread of the wheel, the grouter part having the ends of its branches pivoted to the base of the hook and adapted to swing the toe from its seat on the 35 point side of the hook to the inside of the wheel-rim.

4. An adjustable and foldable grouter attachment for traction-wheels, having in combination, a hook having a stem with an 40 adjustable spoke-clutch, a mud-toe seated on the point side of said hook and hinged to the base of the hook to fold back against the stem.

5. An adjustable and foldable grouter attachment for traction-wheels, having in combination, a hook, a lug on the stem of said hook, a U-shaped yoke with its legs disposed through said lug, nuts threaded on said legs, a bifurcate grouter having the inside of its 50 base shaped to straddle and fit on the point-side of the hook, and the ends of its branches pivoted to the base of said hook, and a tensional spring connected between the grouter and the stem of said hook.

JOHN McDONALD.
